Primary Examiner — Samantha Wood*Assistant Examiner* — Vanessa Martinez**CLAIM**

(57) The ornamental design for a low profile light, as shown and described.

DESCRIPTION

FIG. 1 is a top, front, right side perspective view of a low profile light;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in FIGS. 1-7 illustrate portions for a low profile light that form no part of the claimed design.
